UNITED STATES PATENT OFFICE.

JAMES L. WHITE, OF BUFFALO, TEXAS.

SELF-LIGHTING LAMP-BURNER.

1,277,014.

Specification of Letters Patent. Patented Aug. 27, 1918.

Application filed May 22, 1917. Serial No. 170,226.

To all whom it may concern:

Be it known that I, JAMES L. WHITE, a citizen of the United States, resident of Buffalo, in the county of Leon and State of Texas, have made a certain new and useful Invention in Self-Lighting Lamp-Burners; and I declare the following to be a full, clear, and exact description of the same, such as will enable others skilled in the art 5 to which it appertains to make and use the invention, reference being had to the accompanying drawings, and to letters or figures of reference marked thereon, which form a part of this specification.

15 Figure 1 is a side view of a lamp burner having the invention applied thereto.

Fig. 2 is a section on the line 2—2, Fig. 1.

Fig. 3 is a section on the line 3—3, Fig. 2.

Fig. 4 is a section on the line 4—4, Fig. 3.

20 The invention has relation to means for lighting lamps, having for its object to provide an attachment located near the wick tube of an oil lamp, and having a small pilot light, and means for producing a spark directed toward the wick of the latter.

The invention consists in the novel construction and combinations of parts, as hereinafter set forth.

In the accompanying drawings illustrating the invention is shown the burner of an oil lamp, and 3 is the usual wick tube thereof. 4 is a sparking device consisting of a peripherally roughened igniting wheel 5 and a block 6 of pyrophoric material, the latter carried at the free end of a spring-acting arm 6', pivoted at its other end at 6" between parallel plates 18, carried by the lamp burner and located above the top plate thereof, the igniting wheel being journaled 35 between said plates, in bearings thereof. The igniting wheel is rotated by means of a plate 7, pivoted to the shaft of the igniting wheel and having a lateral toothed portion 8, engaging any one of a series of lateral teeth 9 of said wheel, said plate having a crank extension 10, connected at its lower end with the lower end of an inclined operating lever 12, by a rod 11. The operating lever is provided with lower lugs 12', spaced 40 apart from each other and inclined oppositely to the lever proper, said lugs pivoted at their upper ends 13 to the rim of the burner 2. In this way the operating lever is braced against lateral movement, and is 45 located in exposed position, without said burner. The operating lever being pressed

upwardly, the igniting wheel will be rotated to make the spark.

The operating handle 12, upon release thereof is returned to normal outwardly 60 thrown position by means of a coiled spring 14, having at one end connection with the outer end of the extension 10, and at its other end to the rim of the burner.

The pilot light wick tube 15 is provided 65 with a wick 16, said tube mounted close to the wick tube of the lamp.

A metal plate 17 surrounds the base of the lamp, and is provided with parallel plate extensions 18, spaced apart, overlying and 70 radial with relation to the top of the burner, the pilot light wick tube, and the sparking device being mounted and protected between said plate extensions.

The pilot light wick is fed from a small 75 benzine or gasoline reservoir 19, located under and supported from the burner.

Upon operation of the lever 12, as stated, the resulting spark, directed toward the wick of the pilot, will light the same, the 80 wick of the lamp being in turn lighted by the pilot.

Upon release of the handle, it will be returned to normal position as stated.

An extinguisher cover plate 20 for the 85 pilot normally rests upon the top of the plate extensions 18, and is hinged to the lamp burner at 21, this extinguisher being thrown backwardly before operation of the handle 12, and returned to normal position 90 after the lamp is lighted, by means of an operating rod 21, pivotally engaging the burner at 22 and having operating engagement with the cover plate at 23, said rod having at its free end a handle extension 24, 95 located adjacent to the operating lever for the igniting wheel.

I claim:—

1. In a lamp lighter, an oil lamp burner having a wick tube, parallel plates carried 100 by said burner and located above the top plate thereof, an igniting wheel journaled in bearings of said plates, a spring-acting arm pivoted to said plates and carrying at its free end a block of pyrophoric material 105 pressing upon said wheel, means for turning said wheel including a plate having a crank extension, an inclined operating lever having lower lugs spaced apart from each other, inclined oppositely to the lever proper 110 and pivoted at their upper ends to the rim of said burner, and a connecting rod from

the lower end of said crank extension to the lower end of said lever, the latter located in exposed position outside said burner.

2. In a lamp lighter, an oil lamp burner having a wick tube, parallel plates carried by said burner and located above the top plate thereof, an igniting wheel journaled in bearings of said plates, a spring-acting arm pivoted to said plates and carrying at 5 its free end a block of pyrophoric material pressing upon said wheel, means for turning said wheel including a plate having a crank extension, an inclined operating lever having lower lugs spaced apart from each other, 10 inclined oppositely to the lever proper and pivoted at their upper ends to the rim of 15

said burner, a connecting rod from the lower end of said crank extension to the lower end of said lever, the latter located in exposed position outside said burner, a 20 pilot light, an extinguisher plate therefor hinged to the burner, and an operating rod for said extinguisher pivoted to the burner and having a handle end located adjacent to said lever. 25

In testimony whereof I affix my signature in presence of two witnesses.

JAMES L. WHITE.
